WEB SPLICING DEVICE

Henry A. Wise Wood, New York, N. Y., assignor
to Wood Newspaper Machinery Corporation,
New York, N. Y., a corporation of Virginia

Application August 29, 1932, Serial No. 630,973
Renewed June 19, 1935

3 Claims. (Cl. 242—58)

This invention relates to a device for providing efficient and useful means for splicing a new web roll to a running web coming from an expiring roll.

5 The principal objects of the invention are to provide a new combination of a torque motor driven type of tension device, which, in itself, is old, with means acting between or around the tension members to press the web against the rotating fresh roll; to provide electro-magnetic means for actuating or operating the web pressing means in combination with electro-magnetic means for operating web severing means, acting between or around the tension members; to provide a yielding web tension means actuated to change the tension by mechanical means at the other end thereof in order to prevent the running roll from overrunning and flooding the device with paper, and to combine the same with 15 the other features above mentioned.

20 Other objects and advantages of the invention will appear hereinafter.

Reference is to be had to the accompanying drawing, in which

25 Fig. 1 is an end view of a web splicing device constructed in accordance with this invention, showing the web pressing means just going into action to press the web against the fresh roll in full lines and showing it retracted in dotted lines, and

30 Fig. 2 is an elevation of the bottom of the tension device.

A conventional type of reel 3 is shown for supporting the running roll or exhausting stub A and fresh roll B. This reel is shown as supported on a main shaft 1 carried by a base or pedestals 2 and the reel comprises two spiders between which are mounted the web rolls.

To provide means for rotating the fresh roll 40 B up to web speed a shaft 4 is shown which may be driven from any convenient source of power, such as the printing press itself. Bevel gears 5 and 6 operate a vertical shaft 7, which in turn operates other bevel gears 8 and 9, and a 45 pinion 10 and gear 11. The gear 11 is rotatably mounted on the shaft 1 and has secured to it a large gear 12. The gear 12 meshes with gears 13, one for each of the rolls or spindles. It may be stated that an appropriate clutch may be 50 used for engaging the spindle of the fresh roll and its gear 13 to transmit rotation from the gear 12 to the active spindle to rotate the fresh roll prior to and during splicing. No attempt has been made to show such a clutch and any 55 type of clutch can be used.

On brackets 14 carried by a brace 15, which constitutes a part of the frame of the printing press, is mounted a shaft 16 free to turn in these brackets. On this shaft is carried oscillatably a brush frame 17. This brush frame is adapted to be raised and lowered by swinging it and its shaft 16 by suitable means, either manually operated or motor operated, as desired.

Tension straps 18 are shown as being yieldingly secured at their bottom ends by means of 10 springs 40. These tension straps are carried over individual eccentric pulleys 41 at their upper ends. These pulleys 41 are secured to a shaft 19 which is rotatably mounted in the brackets 14.

A sprocket 20 is carried by this shaft 19, which is operated by a motor 23 through a sprocket 22 thereon and a chain 21. This motor is operated in a direction to serve to keep the tension and prevent the running roll A from 20 overrunning and thereby flooding the paper.

On the frame 17 is carried a shaft 26 capable of turning. Fixed to this shaft are a series of arms 25, each pair of arms carrying a brush 24 so that all these brushes will move together 25 when the shaft is oscillated. These brushes project through spaces between the tension straps 18 so that they can contact with the web W.

For the purpose of accomplishing this there is 30 a solenoid 27 adapted to lift a pivoted latch 28 and release a toe 29 fixed on the shaft 26. When this toe is released, springs 30, acting through stop collars 31, rods 32 and arms 33 secured to the shaft 26, oscillate said shaft and thereby move 35 the brushes forward toward the web and press the web against the fresh roll B.

A solenoid 34 is provided which, when energized, acts through a link 35 and latch 36 to release a toe 37 which is secured to a shaft 38. 40 Securely mounted on this shaft, which is rotatably carried in the brush arm 17 are a series of severing knives 39. A coiled spring 45 then rotates this shaft to project the knives 39 between the tension straps to sever the web.

45 After this operation the brush arm 17 is raised in any desired manner to inoperative position and the fresh roll B then becomes the running roll and is moved by the rotation of the reel into contact with the tension members 18.

50 It will be seen that this device combines electro-magnetic means for operating the web pressing means with electro-magnetic means for operating the web severing means and also combines the torque motor type tension controlling device with 55

means for pressing the web against the rotating fresh web roll to make the paster, and combines the web severing means with the same. In this way efficient and useful mechanism is provided for the splicing of a new web roll to a running web coming from an expiring roll.

The operation has really been stated in describing the mechanism.

Although I have illustrated and described only 10 one form of the invention, I am aware of the fact that modifications can be made therein by any person skilled in the art without departing from the scope of the invention as expressed in the claims. Therefore, I do not wish to be limited in this respect, otherwise than as set forth 15 in the claims, but what I do claim is:—

1. In a web splicing device, the combination with a reel adapted to carry a running roll and a fresh roll, of a frame adapted to be moved from 20 operative to inoperative position, a web-pressing means movably mounted on the frame, a solenoid, a spring-pressed plunger normally held in inoperative position, and means actuated by the last- 25 named means constituting a latch connected with the web-pressing means, said web-pressing means being connected with the plunger, whereby when the said solenoid is energized, the web-pressing means will be released and the plunger

5 moved in a certain direction to actuate the web-pressing means toward the web and the fresh roll, a second solenoid, a web severing means oscillatably mounted and spring actuated, means for holding the severing means in inoperative position, and means operated by the second solenoid for releasing the severing means.

2. In a web splicing device, the combination with a reel adapted to carry a running roll and a fresh roll, of a frame adapted to be moved from 10 operative to inoperative position, a web-pressing means movably mounted on the frame, a solenoid, means whereby when the said solenoid is energized, the web-pressing means will be released and moved in a direction toward the web and the 15 fresh roll, a second solenoid, a web-severing means oscillatably mounted and spring actuated, means for holding the severing means in inoperative position, and means operated by the second 20 solenoid for releasing the severing means.

3. In a web splicing device, the combination of a torque motor type of tension having tension members engaging the surface of the roll, web-pressing means acting between said tension members against the surface of the roll, and means 25 for rotating the fresh roll by power applied to the central axis thereof.

HENRY A. WISE WOOD.
